UNITED STATES PATENT OFFICE

ALBERT CLARKE, OF DES MOINES, IOWA

CLAMP

Application filed April 23, 1929. Serial No. 357,407.

The object of this invention is to provide an improved construction for a clamp which is useful for gripping and securely holding objects of various kinds and sizes.

5 A further object of the invention is to provide an improved clamp having an arm which is arranged for sliding adjustment and another arm which is pivotally mounted and adapted to be moved into clamping engagement by the action of a screw device.

10 A further object is to provide an improved clamping device which may be employed as a hand tool and which may also be used after the manner of a vise.

15 With these and other objects in view my invention consists in the construction, arrangement and combination of the various parts of my device, whereby the objects contemplated are attained, as hereinafter more fully set forth, pointed out in my claim, and illustrated in the accompanying drawings, in which:

Figure 1 is a side elevation illustrating my improved clamp.

20 Figure 2 is a plan view of the same.

Figure 3 is a sectional elevation on the line 3-3 of Figure 1, and illustrating particularly, the slidable arm.

25 Figure 4 is a sectional elevation on the line 4-4 of Figure 1 and illustrating particularly the pivoted arm.

Figure 5 is an elevation partly in section, illustrating the method of using the device as a clamp in connection with a bench or table.

30 The device as shown, includes a base member formed of an elongated bar 10 having an integral standard 11 extending substantially at right angles at one end thereof.

35 A slidable clamping arm 12 is provided and is formed at one end with an apertured boss 13 by means of which it slidably engages the bar 10.

40 The bar 10 may be of any desired shape in cross section. It is here shown as being of cylindrical shape and formed with a longitudinal groove 14. The aperture of the boss 13 is fitted to the cross sectional shape of the bar 10 and suitable means may be provided to keep the arm 12 from turning on the bar. Such means is in this instance, a key 15 en-

gaging the groove 14 and projecting within a notch 16 opening from the aperture of the boss.

45 The free end of the standard 11 is bifurcated and a clamping arm 17 is pivoted between its ends on a pin 18 extending through registering apertures in the bifurcated portion.

50 At its lower end the pivoted arm 17 is formed with a boss 19 having a threaded opening adapted to receive a screw 20. The screw 20 is formed with a head 21 through which an operating handle 22 is slidably mounted.

55 The position of the pivoted arm 17 can be controlled by operation of the screw 20, the inner end of which engages a face 23 formed at the adjacent end of the bar 10 or standard 11, as shown. The face 23 preferably is formed on a curve so that the screw 20 may have a proper engagement therewith, irrespective of the position of the arm 17 by which it is carried.

60 At the free end of the slidable arm 12 there is formed a clamping face 24, which may be of any desired size and shape.

65 A clamping head 25 is formed with a face adapted to coact with the clamping face 24. The clamping head 25 is pivotally attached to the clamping arm 17 by means of a pin or rivet 26 extending through spaced ears 27 on the head and through an aperture in the end portion of the arm.

70 In practical use, the device may be used as a tool by wood workers, mechanics, or other artisans, for the purpose of clamping and holding an object or a plurality of objects.

75 The arms 12 and 17 are first adjusted so that they will be sufficiently spaced apart to accommodate the object or objects to be clamped between them.

80 Then, pressure is applied by turning the screw 20 through the handle 22 for the purpose of moving the arm 17 through an arc to cause the clamping head 25 to approach the clamping face 24. This operation is continued until the object or objects are engaged and securely gripped to the desired extent of pressure.

It is obvious that considerable force can be applied to the screw devices operating upon the pivoted arm and that the threaded engagement of the screw 20 with the threaded boss 19 will cause the parts to remain in any position in which they may be placed manually.

The pivotal mounting of the clamping head 25 permits it to automatically adjust itself to the adjacent face of an object to be gripped as the lever 17 is moved through an arc.

The slidable mounting of the clamping arm 12 permits a considerable range of adjustment and adds greatly to the convenience and usefulness of the device.

The device may also be employed after the fashion of a vise, as illustrated in Figure 5 and for this purpose the slidable arm 12 is removed from the bar 10 by endwise movement.

For this purpose, the device is used with a bench or table such as is illustrated in Figure 5, which may include a top member 28, legs 29, and an apron 30.

An aperture 31 may be formed in a suitable portion of the bench structure, as for instance, in one of the legs 29. The aperture 31 is adapted to receive the elongated bar 10, but if desired, a separate bushing 32 may be employed in the opening 31 within which the bar 10 is fitted for endwise movement. As here shown, a face plate 33 may also be mounted over the outer end of the opening 31 and bushing 32.

When the device is to be used in this manner, the bar 10 is inserted in the opening 31 until the clamping head 25 approaches a portion of the bench structure such as an edge 40 of the top member 28 or a face of the apron 30.

An object to be gripped is then inserted between the clamping head 25 and the bench structure and pressure is applied by turning the screw 20 to cause a pivotal movement of 45 the arm 17.

It is obvious that the bar 10 must fit tightly within the opening in the bench structure or in the aperture of the boss 13 of the slid- 50 able arm 12 so that as pressure is applied, a binding engagement will be produced, which will prevent relative longitudinal movement of the bar 10 with respect to the other member.

I have produced a clamping device which 55 is relatively inexpensive and which is effective in use for a variety of purposes for securely gripping and clamping objects of various kinds, sizes and shapes.

I claim as my invention:

60 A clamping device comprising an elongated bar formed with a standard, a clamping arm slidably mounted on said bar, a clamping arm pivoted between its ends on said standard, and a screw device threaded 65 through one end of said pivoted arm and

adapted for engagement with the adjacent end of the bar for forcing the other end of said arm toward the coacting arm, said bar being formed with an arcuate face for engagement of the end of the screw device at 70 various positions of the pivoted arm.

Des Moines, Iowa, April 2, 1929.
ALBERT CLARKE.
